UNITED STATES PATENT OFFICE.

MARIUS IB NYEBOE, OF COPENHAGEN, DENMARK.

METHOD AND APPARATUS FOR THE WORKING OF PEAT BOGS AND THE LIKE.

Application filed July 13, 1925. Serial No. 43,429.

To all whom it may concern:

Be it known that I, MARIUS IB NYEBOE, a subject of the King of Denmark, and residing at Copenhagen, Denmark, have invented certain new and useful Improvements in a Method and Apparatus for the Working of Peat Bogs and the like, of which the following is a specification.

According to the known methods for extracting peat or mineral earth, greater unearthing plants have been employed in order to obtain a satisfactory working of the peat-bog; e. g. when peat was to be extracted, the plant consisted of a hydraulic excavating or sluicing device loosening the peat and a pumping device sucking up the loosened peat and pumping it away through a piping perpendicular to the edge of the pit so as to carry it to the place where the briquettes or the like are formed. In the said plants the suction pump was placed on a special crane which might be moved along a railway placed along the edge of the peat-bog, so that according to this method a zone of the bog outside the railway was worked. Instead of running on a railway, the crane carrying the suction pump might be placed on a carriage moved along the edge of the peat-pit by means of an endless belt. The width of the zone to be worked by this method could only be 10-15 meters, because a greater width would cause the excavating jets to send the loosened mass away from the suction pump. When such a zone of 10-15 meters was dug out or exhausted, the railway had to be moved a distance away from the edge of the pit corresponding to the width of the zone in order to enable a new zone of this width to be worked. These perpetually repeated removals of the railway combined with the constant relaying of the pipings perpendicular thereto had for their result that the entire plant could work effectively only from one-half to two-thirds of the working time, the rest of the time being occupied in the removal of the railway and the relaying of the piping behind the same according to the removal of the carriage with the suction pump along the railway.

This invention has for its object a method according to which the constant relaying of the railway along which the carriage carrying the suction pump is movable, may be avoided. This is obtained according to the

invention by ramming a pile-bridge into the bog, along which bridge the machines necessary to the digging of the peat are carried to take up the peat at both sides of the bridge and in front of its end, the result of which is that the width of the zone to be worked will be about 60 meters or more.

The invention is especially well adapted for use in connection with the hydraulic excavating or sluicing method, in which case care is to be had that the jet is constantly directed towards the device for sucking up the washed-out mass, so that a displacement of the pile-bridge and piping shall not be necessary too frequently. This method enables 90% or more of the working time to be employed for digging out the bog, while only about 10% of the working time will be occupied in relaying the pile-bridge and the pipings.

In the drawing is represented as much of the invention as is necessary to its understanding, when the sluicing method is employed.

Fig. 1 is a diagram showing how a bog is worked according to the present method.

Figs. 2 and 3 show on an enlarged scale a sectional elevation and a plan, respectively, of a plant according to the invention and working on the washing or spouting method.

According to the present invention shown in Fig. 1 the bog 1 is worked from a pile-bridge 3 laid across the bog, so that the digging may take place at both sides of the pile-bridge and at its end, the pile-bridge and the railway placed thereupon being removed successively as the digging proceeds. The removal of the peat is carried out by a suction pump taking the peat from a channel which extends from the pit under the centre line of the pile-bridge. The sucked-up peat is pumped away through a piping in the direction of the railway.

The specified method enables a zone B to be worked which is several times as broad as the usual zone A.

Figs. 2 and 3 show how the method is carried out. Across the bog the pile-bridge 3 is laid so as to form the support of a railway. Along the latter a carriage 4 carrying the suction pump 5 may be drawn away from the pit successively as the working proceeds. The washing-out of the peat to be sucked up by the pump 5 is carried out by two excavat-

ing devices or injectors 6 working at opposite sides of the bridge 3 and movable along two light railways 7 forming an angle, the opening of which depends on the nature of the bog. The washing devices 6 may also be placed on barges carried along the edges of the pit. The dug-out portion of the bog is designed 8 in Fig. 3, and it will be seen that from this portion of the bog a channel 9 extends under the central line of the pile-bridge 3 somewhat beyond the pump 5, so that the latter will work in a narrow channel or groove communicating with the pit 8. This gives a considerable stability to that portion of the bridge supporting the carriage, as the piles carrying the pumping device are standing in the portion of the bog not yet dug out. At the inner end of the channel 9 generally a third injector 13 is placed, by means of which the channel may be washed out and the peat-mud be kept sufficiently thin. The injectors 6 and 13 receive their water from a high-pressure pump 14 movable on a track 15 or placed upon a barge 25 in the pit. The sucked-up mud is pumped away through the mud-piping 11, 17 to the briquetting machinery or to a collecting pit 18, from which a special mud-pump 19 pumps it further on to the briquetting machinery. Dug-out roots may be removed either by means of preferably rake-like devices moved to and fro along that portion of the bridge which stands in the pit 8, or by a man working from a bridge 10 placed where the channel 9 opens out into the pit 8. They may also be removed by a crane placed at the edge of the pit.

Successively as the working proceeds the carriage 4 with the suction pump 5 is drawn away from the pit 8, and at the same time the pipe 11 is shortened. When the carriage 4 is moved to the right in Fig. 3, the superfluous portion of the bridge standing in the pit 8 is removed, which may be done either from the remaining portion of the bridge or from a barge 12 floating in the pit 8. The piles may also be washed out.

If the bog is sufficiently firm, no actual pile-bridge is required, but the suction device may run upon a track supported by sleepers lying across the channel or groove 9. When the suction device is placed on a carriage running upon an endless belt, the construction of an actual transport way across the bog may likewise be avoided.

The angle between the light railways 7 on which the washing devices 6 run, varies, as stated above, somewhat according to the consistence of the surface of the bog; generally, however, care is taken that the pile-bridge 3 is placed in the medial line of the angle.

Besides being used for the extraction of peat, the specified method may also be employed for the digging of draining channels in a peat-bog or in mineral earth. In these

cases the sucked-up peat-mass may be discharged through mud-pipes over greater or smaller areas of the bog instead of being laid, as is otherwise the case, along the sides of the channel, whereby these sides are liable to slide down.

The details specified above may be varied without departing from the principle of the invention.

I claim:

1. A method of working peat bogs or the like, comprising the steps of sinking a pile bridge into the bog; excavating the peat at opposite sides and in front of such bridge; and moving along said bridge machinery for withdrawing the excavated peat.

2. A method of working peat bogs or the like, comprising the steps of sinking a pile bridge into the bog; hydraulically excavating the peat at opposite sides and in front of such bridge; and moving along said bridge machinery for withdrawing the excavated peat.

3. A method of working peat bogs or the like, comprising the steps of sinking a pile bridge into the bog; hydraulically excavating the peat at opposite sides and in front of such bridge; and moving along said bridge a suction pump for withdrawing the excavated peat.

4. A method of working peat bogs or the like, comprising the steps of sinking a pile bridge into the bog; excavating the peat at opposite sides and in front of such bridge; and moving along said bridge a suction pump for withdrawing the excavated peat.

5. A method of working peat bogs or the like, comprising the steps of sinking a pile bridge into the bog; hydraulically excavating the peat at opposite sides and in front of such bridge along two lines which converge in angular relation toward the bridge; and moving along said bridge machinery for withdrawing the excavated peat.

6. A method of working peat bogs or the like, comprising the steps of sinking a pile bridge into the bog; hydraulically excavating the peat at opposite sides and in front of such bridge along two lines which converge in angular relation toward the bridge so that the latter bisects the angle formed by said lines; and moving along said bridge machinery for withdrawing the excavated peat.

7. A method of working peat bogs or the like, comprising the steps of sinking a pile bridge into the bog; forming a channel leading from the bog beneath such bridge; excavating the peat at opposite sides and in front of the bridge; and moving a suction device along that part of the bridge which overlies the channel to withdraw the excavated peat therefrom.

8. A method of working peat bogs or the like, comprising the steps of sinking a pile bridge into the bog; forming a channel lead-

ing from the bog beneath such bridge; excavating the peat at opposite sides and in front of the bridge; sluicing water into said channel at the inner end thereof; and moving a suction device along that part of the bridge which overlies the channel to extract the peat and water therefrom.

9. A peat-working installation, comprising a pile bridge extending into the pit in a bog being worked; a carriage mounted to travel along such bridge; and machinery for excavating peat at opposite sides and in

front of the bridge, connected with the carriage to be shifted thereby.

10. A peat-working installation, comprising a pile bridge extending into the pit in a bog being worked; a carriage mounted to travel along such bridge; machinery for excavating peat at opposite sides and in front of the bridge; and a suction device mounted on said carriage for withdrawing the excavated peat.

In testimony whereof I affix my signature.
MARIUS IB NYEBOE.
